[57] CLAIM

The ornamental design for a computer housing, as shown and described.

DESCRIPTION

FIG. 1 is a top, front, perspective view of the computer housing showing my new design;

FIG. 2 is a top, plan view thereof on a reduced scale;

FIG. 3 is a side, elevation view thereof on a reduced scale, the opposite side being a minor image;

FIG. 4 is a rear elevation view thereof on a reduced scale; and

FIG. 5 is a bottom, plan view thereof on a reduced scale.

The broken lines in FIG. 1 are shown for illustrative purposes only.

FIG. 1

FIG. 2

FIG. 3

FIG. 4

FIG. 5
